ENGINE CUT-OFF

Joyce O. Everett, Lima, Ohio, assignor to The Buckeye Machine Company, Lima, Ohio, a corporation of Ohio

Application August 21, 1933, Serial No. 686,182

5 Claims. (Cl. 74—2)

This invention relates to control mechanism and has for its object the provision of a simple and efficient device which will operate efficiently to stop an engine in the event of any abnormal conditions causing a stoppage or excessive decrease of pressure in either the oil or the water line. The invention provides a very simple and compact device which will be held against action to stop the engine under normal conditions, and which will operate with certainty to stop the engine when an abnormal condition arises and will then hold the governing mechanism in the inactive position until manually re-set. The invention is illustrated in the accompanying drawings and consists in certain novel features which will be hereinafter first fully described and then more particularly defined in the appended claims.

In the drawings, Fig. 1 is a front elevation, partly in section, of a Diesel engine having the invention applied thereto,

Fig. 2 is an enlarged vertical section through the controlling mechanism,

Fig. 3 is a section on the line 3—3 of Fig. 2, Fig. 4 is a section on the line 4—4 of Fig. 2.

The reference numeral 1 is applied upon the drawings to indicate the front plate of a Diesel engine and it may be noted that this front will be common to all the engines in a gang of engines. Mounted upon the front plate 1 is a setting lever 2 which is carried by a rock shaft or fulcrum 3 journaled in the front plate, as shown clearly in Fig. 2. The lower fulcrum end of the lever 2 is formed into an enlarged circular head 4 carrying a latch 5 which is slidably mounted in a socket 6 provided therefor upon the head 4 and is yieldingly held to the front plate 1 by an expansion spring 7 housed in the socket. The latch is provided with an enlargement or abutment 8 against which the rear end of the spring presses and at the front side of the head the latch is equipped with a knob or other form of handle 9 by which it may be manually manipulated. The head 4 is also provided in its side with an opening 10 which is preferably located at a point approximately diametrically opposite the socket 6. The fulcrum or rock shaft 3 extends through a sleeve 11 which is secured in the front plate 1 and the rear end of the fulcrum or shaft 50 extends beyond the rear end of said sleeve, the rear end of the sleeve constituting an abutment against which a cam 12, secured upon the fulcrum, bears while the front end of the sleeve bears against a hub or boss 13 formed on the inner side of the head so that endwise move-

ment of the shaft and the head will be prevented. A lay governor shaft 14 is slidably supported upon the engine frame at the rear of the front plate 1 and adjacent the rear end of the fulcrum 3, as shown clearly in Fig. 2, and this lay governor shaft extends across the entire gang of engines and has secured thereon, at proper intervals, arms 15 which rise therefrom and correspond in number to the engines in the gang of engines, one arm being provided for each engine. The arms 15 each carries at its upper end a pump meter rod 16 which controls the pump associated with each engine so that, in one position of the meter rod, the pump will be permitted to operate and in another position it will be cut off from operation. Adjacent the cam 12, an abutment or collar 17 is secured upon the governor shaft 14 and the cam or eccentric 12 bears against said collar in the operation of the device. The cam is provided on its front face with a reinforcing rib 18 and fitted in this rib is a pin or bolt 19 about which is engaged the hooked lower end 20 of a contractile spring 21, the pin being normally at one side of the vertical plane of the fulcrum and the upper end of the spring being engaged with an anchoring rod 22 which is firmly secured in some fixed part of the engine frame or support above the governor shaft and the setting lever. It will now be understood that when the parts are in the positions illustrated, the engine will be permitted to operate, and when the engine is to stop, the setting lever is swung downwardly to the left through an arc of 90° so that the high part of the cam 12 will bear against the collar 17 and move it and the governor shaft to the right in Fig. 1. The arm 15 and the metering rod 16 will, of course, follow the movement of the governor shaft and the operation of the pump will be stopped. When the setting lever is thus swung downwardly, the latch 5 will automatically engage in a socket provided therefor in the front plate 1, as will be understood.

In carrying out the present invention, there is secured upon the front plate of the engine, below the head of the setting lever, a housing 23 within which are mounted bellows 24 and 25, the lower ends of which communicate directly with the oil line 26 and the water line 27, respectively. The upper ends of the bellows are closed and bear against a cage 28 which is supported solely by the bellows and is provided with a socket member 29 depending between the bellows, as clearly shown in Fig. 3. A latch pin 30 extends through the socket 29, axially thereof, and has its ends projected through the top and bottom, respective-

ly, of the housing 23, the upper end of this latch being arranged to engage the opening 10 in the head of the setting lever and the lower end thereof being formed into a crank 31 terminating in a 5 knob 32. An expansion spring 33 is housed in the socket 29 and bears at one end against the base of said socket and at its opposite end against the top of the housing, as clearly shown.

As long as the conditions under which the engine 10 is operating remain normal the bellows 24 and 25 will be expanded by the pressure exerted thereon through the oil and water lines. Should a leak in either line develop or for any other reason the pressure exerted thereby upon the respective bellows should drop, the bellows will contract and the spring 33 will then at once expand and cause the cage 28 to move downwardly in the housing and thereby withdraw the latch pin 30, which is pinned to the cage, as shown at 34, out 15 of engagement with the opening 10 whereupon the spring 21 will at once contract and exert an upward pull upon the pin 19 so that the cam 12 and the fulcrum 3, to which the cam is secured, will be rocked in the proper direction to actuate 20 the governor shaft 14 and the meter rod to stop the action of the pump, as previously stated. When the spring 21 thus actuates the cam, the setting lever will, of course, be swung downwardly and the latch 5 will automatically engage the 25 socket provided therefor in the front plate of the engine so that the parts will be held in the inoperative positions until the attendant manually re-sets the device.

From the foregoing description, taken in connection 30 with the accompanying drawings, it will be seen that I have provided a very simple and compact mechanism which may be installed at a very slight expense and will operate efficiently at all times. While the invention, in one specific 35 form, has been set forth herein as applied to a Diesel engine, it will function successfully in other applications and may be applied to any apparatus employing water-cooled or oil-cooled bearings or which effects lubrication by oil under pressure.

Having thus described the invention, I claim:

1. The combination with a setting lever having a lateral head, of yieldable means tending constantly to swing the lever to cut off position, a latch pin normally engaged in the lateral head of 40 the lever to hold it in working position, and pressure controlled means for withdrawing said latch pin upon decrease of pressure in either of said lines.

2. In combination with an engine-setting lever provided with a lateral head having an opening, a latch pin slideable to and from and normally engaging in said opening in the head of the lever, pressure controlled means for retaining the latch pin in engagement with the opening in the head of the lever, and yieldable means tending constantly to withdraw the latch pin whereby upon decrease of the pressure the setting lever will be released.

3. The combination with the setting lever of an engine, of a latch arranged to engage the head of the lever and normally hold it in operative position, yieldable means tending constantly to swing the lever to inoperative position, bellows disposed adjacent the latch and connected with the oil and water lines of the engine to be normally held expanded by the pressure in said lines, a cage supported by said bellows and secured to the latch, and a spring acting constantly on the 20 cage in opposition to the bellows whereby upon decrease of pressure in either the oil or the water line the latch will be withdrawn and the setting lever swung to inoperative position.

4. The combination of a lay governor shaft, a 25 meter rod connected with said shaft to move therewith, an abutment on the shaft, a setting lever, a fulcrum for said lever rotatably mounted and having one end disposed adjacent the governor shaft, a cam secured on the end of the 30 fulcrum and arranged to bear against the abutment on the governor shaft, a retractile spring attached to the cam and to a fixed point and tending constantly to swing the high part of the cam against the abutment, a latch carried by the 35 setting lever and arranged to hold the lever in inoperative position, a second latch normally engaging the setting lever and holding it in operative position, and means controlled by the pressure in the oil and water lines of the engine to release 40 the second latch upon decrease of pressure in either of said lines.

5. The combination with a control lever, of a fulcrum carrying the lever, a cam fixed on the fulcrum and arranged to shift a controlled element, means acting on the cam to turn it and the control lever to stop position, a latch normally holding the control lever in working position, and pressure-control means for releasing the latch.

JOYCE O. EVERETT. [L. S.] 50
